COLLAPSIBLE CART OR THE LIKE

Dennis Berlin, Philadelphia, Pa.

Application February 7, 1955, Serial No. 34,385

Term of patent 14 years

(Cl. D14—3)

Fig. 1 is a perspective view of a collapsible cart or the like embodying my new design.

Fig. 2 is a perspective view of the frame portion of the collapsible cart in a collapsed position.

The opposite sides not shown in Fig. 1 are the same as the sides shown.

I claim:

The ornamental design for a collapsible cart or the like, substantially as shown and described.
